UNITED STATES PATENT OFFICE.

ERNEST GIFFHORN, OF NEWARK, NEW JERSEY.

RUPTURE OR HERNIA TRUSS.

Application filed November 20, 1925. Serial No. 70,252.

This invention relates, generally, to improvements in trusses; and, the present invention has reference, more particularly, to a novel construction of rupture or hernia support which shall give great comfort to the wearer, which is readily applicable to the body, and is provided with adjusting means, whereby the truss may be made to assume variously desired positions with relation to the contour of the human body, and thus to provide the greatest comfort possible.

The present invention, therefore, has for its principal object to provide a novel and simply constructed rupture or hernia-truss, with the main body-portion of which is associated and connected therewith by means of a hinge an arc-shaped metal reenforced fastening strap, provided at or near the hinge-connection with a means of adjustment, whereby the strap may be brought closer to or farther away from the body of the wearer, when fastened to the pad-portion of the truss-body, thus leaving an air-space between the body of the wearer and the fastening strap.

Such space, and consequent removal of pressure from against the body and the leg at that point, prevents compression of the blood vessels, thus permitting of a free circulation of the blood, furthermore permitting free movement of the leg, at the joint and not interfering with the action of the muscles, so that the person will not go lame and that there will be no pain.

The invention has for its further object to provide in connection with the main body of a rupture or hernia-truss, a curved or arc-shaped metal-reenforced strap, usually a steel band is used, so as to provide a substantially rigid or stiff strap; and, furthermore, to provide in connection with a simple hinge between the truss-body and the strap, a readily manipulatable adjusting screw placed in such a position and at the proper point, that the exact pressure is placed upon the body of the wearer where it is most needed so that the greatest comfort to the wearer of the truss will be the result.

Other objects of the present invention not at this time more particularly enumerated will be fully understood from the following detailed description of the present invention.

With the various objects of the present invention in view, the said invention consists, primarily, in the novel rupture or hernia-

truss hereinafter set forth; and, the said invention consists, furthermore, in the general arrangements and combinations of the various devices and parts, as well as in the details of the construction of the said parts, all of which will be more fully described in the following specification, and then finally embodied in the clauses of the claims, which are appended to and which form an essential part of the said specification.

The invention is illustrated in the accompanying drawings, in which:—

Figure 1 is a perspective view of the rupture or hernia-truss, showing the manner of applying the truss to the body of the wearer; and Figures 2 and 3 are edge views of the truss, Figure 2 illustrating one of its adjusted positions about the body, and Figure 3 showing the truss-body and its attaching strap, in their disconnected relation, for removal of the truss from the human body.

Figure 4 is a perspective view of fragmentary portions of the truss-body and of the strap, showing more particularly the hinge-connection between said members, the parts of the said connection, however, being illustrated in their separated relation.

Figure 5 is a top edge-view of the truss, on an enlarged scale, that portion of the truss-body provided with the rupture or hernia-pad being omitted from said view, Figure 6 is a face view of the hinge-connection of the members of the truss, looking in the direction of the arrow α in said Figure 5; and Figure 7 is an edge-view of the said hinge-connection, the members of the hinge being shown in their disconnected relation.

Similar characters of reference are employed in the said above described views, to indicate corresponding parts.

Referring now to the said figures of the drawings, the reference-character 1 indicates a rupture or hernia-truss embodying the principles of the present invention, the same comprising a main body-portion 2 provided with the inside lumbar cushion 3, and at its end-portion 4, with the hernia-pad 5 of any usual construction. The reference-character 6 indicates the usual curved and flat metal member of the said body-portion 2, made of suitable spring-metal, and the same being suitably encased in cover-sections 7 and 8, usually of leather, rubber, or of any other suitable material. The said metal member 6 also has an end-portion 9 of suitable length, projecting from the end-

portion 10 of the casing or envelope formed by the cover-sections 7 and 8, the said end-portion 9 being provided with a hinge-plate 11 formed with suitable pintle-receiving eyes or loops 12.

The reference-character 13 indicates the fastening member of the truss, the same consisting, essentially, of a curved and flat metal member 14, made of suitable spring-metal, 18 suitably encased in cover-sections 15 and 16, made of leather, rubber, or other suitable material. Connected with and extending from the end-portion 17 of one of said cover-sections is a strap-member 18, usually 15 provided with holes or perforations 19 for attachment of said strap-member over a stud or pin, as 20, with which the hernia-pad 5 may be provided.

Extending from the end-portion 21 of 20 the casing or envelope formed by the cover-sections 15 and 16 is a portion 22 of said metal member 14 which is formed with an eye or loop 23, adapted to be fitted between the eyes or loops 12, as shown in Figure 6 25 of the drawings, the several eyes or loops being pivotally connected by means of a pintle 24, so as to provide a suitable hinge-connection, as will be evident from an inspection of Figures 1, 5 and 6 of the drawings. Upon 30 its inner side the strap-member, thus produced, may also be suitably padded, as at 25, if desired. The end-portion 22 of said metal member 14 is made with a screw-threaded hole 26 in which is arranged an 35 adjusting set-screw 27 having its end 28 bearing upon the projecting portion 9 of the metal member 6, and being provided with a head 29, or other suitable means for manipulation and desired adjustment of the said set-screw 27.

In use the main body-portion 2 of the truss is placed about the waist of the user, as indicated in Figure 1 of the drawings, with the hernia-pad 5 placed directly over the rupture of the wearer's body, the spring-like action of the metal band 6 holding the said body-portion 2 in proper position. The hinged member 13 of the truss is then brought over the hip-portion of the wearer's body, as shown in Figure 2, and the strap portion 18 is fastened by means of its perforations 19 to the stud or pin 20 of the hernia-pad 5. By proper adjustment of the set-screw 27, the curved member 13 may be 55 brought closely to or farther away from the contour of the hip-portion of the body, so as to provide an open space, as 30, as indicated in said Figure 2 of the drawings. In this manner, an air-space which prevents heating and sweating, and furthermore prevents irritation is provided, so as to give 60 ease and comfort to the patient. At the

same time, all pressure is removed from the blood-vessels at that point, so that the circulation of the blood is not interfered with, 65 and, furthermore, there being no pressure exerted upon the muscles at the point, the leg-motion is not obstructed, so that the patient can walk without any usual limp, and without pain.

Of course, I am aware, that my present invention is capable of some changes in the general arrangements and combinations of the various devices and parts, as well as in the details of the construction of the said parts, as set forth in the foregoing specification, and as defined in the clauses of the claims which are appended to the said specification. Hence, I do not limit my present invention to the exact arrangements and 75 combinations of the various devices and parts as described in the said specification, nor do I confine myself to the exact details of the construction of the said parts, as 80 illustrated in the accompanying drawings. 85

I claim:—

1. In a truss a bowed main body-portion, a fastening-portion, the adjoining ends of said body-portion and fastening-portion being hinged together in overlapping relation 90 to provide the former with an end member underlying the latter, and an adjustable set-screw threaded through said fastening portion to bear against said end member of said body-portion whereby both spacing of said fastening portion away from the wearer's body and regulation of the tension exerted thereby on the body-portion is attained.

2. A truss comprising a bowed main body-portion having a hernia-pad adjacent to its free end, a fastening-portion, the adjoining ends of said body-portion and fastening-portion overlapping to provide the former with an end member underlying the latter, means to pivotally interconnect said body and fastening portions in such relation, cooperative means to separably fasten the free meeting ends of said body and fastening portions together, and an adjustable set-screw threaded through said fastening portion to bear 100 against said end member of said body-portion whereby both spacing of said fastening portion away from the wearer's body and regulation of the tension thereof is attained. 105

3. In a truss as defined in claim 2, enveloping covering means for said body and fastening portions, and a lumbar-pad attached to the inner side of said body-portion and its covering means.

In testimony, that I claim the invention 115 set forth above I have hereunto set my hand this 19 day of November, 1925.

ERNEST GIFFHORN.
